ALFRED KÄSTNER, OF ESSEN-ON-THE-RUHR, GERMANY, ASSIGNOR TO FRIED. KRUPP AKTIENGESELLSCHAFT, OF ESSEN-ON-THE-RUHR, GERMANY.

LOADING DEVICE FOR PORTABLE GUNS.

1,040,210.

Specification of Letters Patent.

Patented Oct. 1, 1912.

Application filed March 1, 1910. Serial No. 546,651.

To all whom it may concern:

Be it known that I, ALFRED KÄSTNER, a subject of the Emperor of Germany, and a resident of Essen-on-the-Ruhr, Germany, 5 have invented certain new and useful Improvements in Loading Devices for Portable Guns, of which the following is a specification.

The subject of the present invention 10 constitutes a loading device for those portable guns, the barrels of which are adjustable laterally, relatively to the undermount.

The purpose of the invention is to so 15 arrange the loading device that the ammunition can be presented in line with the axis of the bore, even when the gun barrel has been swung to one side on the mount. This purpose is attained, according to the invention, by having the loading tray, intended 20 to receive the ammunition, shiftable in a guide on its carrier that is arranged upon the mount, the said guide being concentric with the vertical axis about which the gun barrel swings in its lateral adjustment.

25 One embodiment of the present invention is shown, by way of illustration, in the accompanying drawings, in which—

Figure 1 is a side view of the loading device and the parts of a portable gun there- 30 with concerned; Fig. 2 is a top plan view of the parts shown in Fig. 1, adjusted to another position; Fig. 3 is a section on the line 3—3 of Fig. 2, on a larger scale; Fig. 4 is a section on the line 4—4 of Fig. 3, seen from 35 the left; Fig. 5 is a top plan view of Fig. 3, partly in section, and with the loading tray omitted; Fig. 6 is a section on the line 6—6 of Fig. 5; and Fig. 7 is a section on the line 7—7 of Fig. 3, seen from the right.

40 The gun barrel A is guided upon the slide-track carrier P, which is swingingly mounted through the medium of horizontal trunnions p' in the upper-mount R. The upper-mount R is supported on the undermount B and is adapted to swing thereon about the axis of a vertical trunnion r', a bearing b' for which is provided in the undermount. For swinging the upper-mount R relatively to the undermount B, a suitable training 45 mechanism (not shown in the drawing) will be introduced between the upper and under mounts. Furthermore, it will be assumed that a suitable elevating mechanism (not shown) will be introduced between the up-

per-mount R and the slide-track carrier P, 55 through the medium of which the slide-track carrier is swung about the axis of the horizontal trunnions p'. The training means can be of any desired construction.

The loading apparatus is as follows:— 60 Upon each of the two cheeks of the undermount B and upon the bearings b² (Figs. 1 and 2) are jointed a pair of links C. The axes of the bearings b² are perpendicular to the vertical plane of the longitudinal axis of 65 the gun. Each pair of links C has jointed connection with a frame D. Upon the frame D is secured a table S, upon which a slide E is movably guided. With the slide E, the loading tray F, which serves to receive the am- 70 munition T (Fig. 1) is removably connected. Each pair of links C constitute together with the appurtenant cheek of the undermount B and the appurtenant frame D, a jointed parallelogram. Each of the frames 75 D has two different lengthed perpendicular legs d' and d² through which it rests in the laid-over position of the loading device (compare broken line position in Fig. 1 and full line position in Fig. 2) upon yielding abut- 80 ments b³ (Fig. 1) which are arranged upon the inclined cover plate B⁴ (Fig. 2) of the undermount. For guiding the slide E upon the table S, a claw e' serves, which is pro- 85 vided on the side of the slide presented toward the gun barrel and extends over the entire breadth of the slide; also a pair of claws e² mounted on the side of the slide away from the gun barrel. The claws e' and e² grip the corresponding edges of the 90 table S and are guided upon these edges. The abutting vertical guiding surfaces of the aforesaid guiding parts are curved on an arc whose center coincides with the axis of the trunnion r', when the loading device as- 95 sumes the loading position indicated in full lines in Fig. 1. For reducing friction between the table S and the slide E, rollers G are provided which are journaled in the housing e³, mounted upon the slide E. The table S 100 has two abutments s' and s² (Figs. 4 and 5) which limit the movement of the slide E upon the table S.

The upper walls of the roller housings e³ are curved (Figs. 4 and 7) and designed to 105 carry the loading tray F. For connecting the latter with the slide E, the following arrangement serves. Arranged upon that

side of the slide E which is turned toward the gun barrel A, is a claw e^4 beneath which a corresponding claw f^1 on the loading tray F can engage (Fig. 3). Furthermore, the slide E is provided on its side presented away from the gun barrel with two hooked-shaped projections e^5 (Figs. 3 to 5). With these projections, a broad nose k^1 of a bolt K (Figs. 4 and 7) can enter into engagement, this bolt being mounted in a housing f^2 on the under side of the loading tray F and acted upon by a spring k^2 . The projections e^5 are provided with bevels e^6 , which act upon the corresponding incline k^3 of the nose k^1 of the bolt K and press the latter into the housing f^2 when the loading tray F is placed upon the slide E. Between the projections e^5 and upon a bolt i^3 resting in these projections, is mounted a weighted lever J. This lever is provided with a spur tooth i' (Figs. 3 and 5) which can enter into engagement with seats s^3 (Figs. 3, 5 and 7) which is provided in the table S. To each of the rests s^3 , corresponds a division mark of an angle scale s^4 (Fig. 5) which is located upon the table S. The pointer belonging to the scale s^4 , is provided by the longitudinal edge e^7 (Fig. 5) of the slide E. The lever J carries a finger i^2 , by means of which the nose k^1 of the bolt K can be thrown out of engagement with the projections e^5 , by throwing the lever J. Secured to a flange of the loading tray F is an annular buffer f^8 (Figs. 1 and 2) of rubber or the like. Through the medium of this buffer, the loading tray abuts against the breech of the gun barrel, when the loading device is swung into the loading position. At the base of the loading tray, there are two keepers f^4 (Figs. 1 and 2) for the carrying bars N (Fig. 2).

Previous to loading the gun, the loading device assumes the position shown in Fig. 2. After the nose k^1 of the bolt K has been moved out of engagement with the projection e^5 of the slide E, through the lifting of the hand lever J acting through the medium of the finger i^2 , the loading tray is lifted from the slide. The ammunition is then brought to the gun upon the loading tray and the loading tray is again placed in position upon the slide E, the claws f^1 and e^4 being brought into engagement with each other. If the loading tray is now pressed downward, the bolt K is pressed backward by the impingement of its inclined face k^3 with the inclined face e^6 of the projections e^5 and is then brought into the locking engagement with the projections e^5 , by means of its spring k^2 . In case the gun barrel, which has been brought into loading position previous to loading, for example, by means of the elevating mechanism, has been swung laterally from its intermediate position, the loading tray, together with the slide E, is pushed to the right or to the left until the edge e^7 of the slide registers with that division mark of the scale s^4 which corresponds to the lateral training imparted to the gun barrel. Before sliding the slide E, the tooth i^1 of the lever J is moved by raising the lever, out of engagement with the engaged seat s^3 of the table. After moving the slide E, the lever J is again released so that it turns itself under the action of its own weight back to the position in which its tooth i^1 engages in one of the seats s^3 . Finally, the loading device is swung through the medium of the bars N, toward the gun barrel. When the loading tray abuts against the breech of the gun barrel, through the medium of the buffer f^8 (Fig. 1) it is suddenly arrested, while the ammunition T, in consequence of its developed inertia, slides partially into the chamber of the gun barrel. After the ammunition has been completely introduced, through the medium of a rammer, the loading device is again thrown back.

Having thus described my invention, what I claim as new therein and desire to secure by Letters Patent is:—

1. In combination with a portable gun having an undermount and an upper-mount laterally adjustable thereon about a vertical axis; a loading device comprising a suitable carrier mounted upon the undermount and a loading tray suitably mounted upon said carrier with lateral adjustment in an arc concentric with the vertical axis of lateral adjustment of the upper-mount. 95
2. In combination with a portable gun having an undermount and an upper-mount laterally adjustable thereon about a vertical axis; a loading device comprising a carrier mounted upon the undermount and movable longitudinally of the gun, and a loading tray supported by said carrier and movable thereon laterally in an arc concentric with the vertical axis of adjustment of the upper-mount. 105
3. In a loading device for portable guns having an undermount and in which the gun barrel swings laterally upon a vertical trunnion, a carrier having freedom of longitudinal movement on the undermount, a loading tray mounted upon said carrier with lateral adjustment and a guide enforcing movement of the tray upon the carrier, in an arc concentric with the center of lateral adjustment of the gun barrel. 115
4. In a loading apparatus for portable guns having an undermount and a barrel laterally adjustable relatively to the undermount, a loading tray adapted to receive the ammunition, a suitable carrier arranged upon the undermount and upon which said loading tray is mounted, and a connection between the loading tray and the carrier, which permits lateral adjustment of the 125
- 65

- loading tray and guides it in an arc concentric with the center of lateral adjustment of the gun barrel.
5. In a loading device for portable guns having a barrel laterally adjustable about a vertical pivot, a carrier and a loading tray removably mounted on said carrier and adjustable thereon in an arc concentric with the vertical pivot of the gun barrel.
10. 6. In a loading device for a portable gun having a barrel adjustable horizontally upon a vertical trunnion, a suitable carrier, a slide mounted upon said carrier and laterally adjustable thereon in an arc concentric with the axis of the vertical trunnion of the gun barrel, and a loading tray mounted upon said slide.
7. In a loading device for a portable gun having a barrel adjustable horizontally upon a vertical trunnion, a suitable carrier, a slide mounted upon said carrier and laterally adjustable thereon in an arc concentric with the axis of the vertical trunnion of the gun barrel, and a loading tray removably mounted upon said slide.
8. In a portable gun having an undermount and a barrel laterally adjustable about a vertical axis; a loading device comprising a table longitudinally movable upon the undermount, a slide mounted upon said table with lateral movement and a guide causing the slide, in its lateral movement, to follow a path concentric with the vertical axis of lateral adjustment of the gun barrel.
30. 9. In a portable gun having an undermount and a barrel laterally adjustable about a vertical axis upon said undermount; a loading device comprising a table movable longitudinally upon the undermount, a slide having roller bearings located to permit the slide to move laterally upon the table, means causing the slide to travel in a path concentric with the vertical axis about which the gun barrel is adjusted and a loading tray mounted upon said slide.
40. 10. In a portable gun having an undermount and a barrel laterally adjustable about a vertical axis upon said undermount; a loading device comprising a table, a slide, rollers through the medium of which the slide is movably mounted upon the table, a loading tray, and housings for the rollers constructed to provide a seat to the loading tray.
50. 11. In a portable gun having a laterally adjustable barrel, a loading means comprising a suitable carrier, a slide mounted on the carrier, a loading tray mounted upon the slide, and readily releasable means for connecting the loading tray with the slide comprising a pair of interengaging claws mounted respectively on the loading tray and the slide and a locking bolt and its seat also mounted respectively upon the loading tray and slide.
60. 12. In a portable gun having an undermount, a barrel laterally adjustable upon said undermount, a suitable carrier, hinged to the undermount, a loading tray mounted on the carrier and readily releasable means for securing the loading tray to its carrier, consisting of claws and an automatic engaging latch preventing longitudinal and lifting movement of the loading tray on its carrier, said carrier constructed to transfer the ammunition to the gun in a horizontal position.
70. 13. In a loading device for portable guns having a barrel laterally adjustable upon a vertical trunnion, a slide laterally adjustable around the axis of said trunnion and having means adapting it to receive and support the ammunition, and a toothed locking gear for locking the slide in adjusted position comprising a dogging tooth mounted upon one of the parts to be interlocked and a series of notches mounted on the other of said parts in position to receive said dogging tooth.
80. 14. In a portable gun having a laterally adjustable barrel, a laterally adjustable loading means comprising a suitable carrier movable longitudinally on the gun, a slide, having means through which it is adapted to receive and support the ammunition, laterally adjustable on the carrier to permit it to present the ammunition in line with the bore of the gun, and an indicator for determining the extent of lateral adjustment of the slide previously to advancing the loading device to the gun barrel.
90. 15. In a loading device for a portable gun having laterally adjustable barrel, a carrier movable longitudinally on the gun and having means for receiving ammunition laterally adjustable relatively to the carrier for the purpose of presenting the ammunition in line with the bore of the gun barrel, an indicator to permit of preadjustment of the ammunition receiving means to correspond with the lateral adjustment of the gun barrel, and means for fixing the ammunition receiving means in the position to which it is adjusted.
100. 16. In a loading device for portable guns having laterally adjustable barrels, a suitable carrier, an ammunition receiving means mounted with lateral adjustment on said carrier and means for interlocking said parts to fix the lateral adjustment of said ammunition receiving means comprising a pivoted lever having a dogging tooth, mounted upon one of the parts to be interlocked and a series of notches or seats mounted on the other of said parts in position to receive said dogging tooth.
110. 17. A loading device for portable guns having laterally adjustable barrels comprising a suitable carrier, a slide mounted on said carrier with lateral adjustment, means for interlocking the slide with the carrier

for the purpose of fixing the lateral adjustment, consisting of a lever mounted on the carrier and having a dogging tooth adapted to engage the slide in the different positions 5 of the latter, a loading tray fitted to said slide, readily releasable means for interlocking the loading tray with the slide, and means carried by the said lever for releasing the means, which interlocks the tray with 10 the slide.

18. In a loading device for guns having laterally adjustable barrels, the combination 15 of a suitable carrier, a slide mounted upon said carrier with lateral adjustment, a pivoted lever mounted on the carrier having a dogging tooth adapted to engage the slide

to fix it in different positions to which it is adjusted, a loading tray mounted upon the slide, a latching bolt for preventing displacement of the loading tray from the slide 20 and a finger carried by the lever adapted to displace the latching bolt and release the loading tray when the lever is moved to a position, which brings its dogging tooth out of engagement with the tray. 25

The foregoing specification signed at Bar-
men, Germany, this 15th day of February,
1910.

ALFRED KÄSTNER. [L. S.]
